UNITED STATES PATENT OFFICE.

FREDERICK M. SINGER, OF RACINE, WISCONSIN.

GOLF-BAG SUPPORT.

Application filed September 12, 1927. Serial No. 218,965.

The invention aims to provide a new and improved leg-equipped support in which the legs are normally folded substantially against the bag but may readily be extended 5 to support said bag in an inclined position, allowing the various clubs to be readily taken from and inserted into the bag.

With the foregoing in view, the invention resides in the novel subject matter herein- 10 after described and claimed, the description being supplemented by the accompanying drawing.

Fig. 1 is a side elevation of a golf bag embodying the invention.

15 Fig. 2 is a side elevation partly broken away and in section, looking in the direction of the arrow A of Fig. 1.

The drawing above briefly described, may be considered as illustrating the preferred 20 form of construction and while this construction will be herein specifically explained, it is to be understood that within the scope of the invention as claimed, variations may be made.

25 The numerals 3 and 4 on the drawing denote upper and lower bands to surround the ends of a golf bag B, any desired means such as the tongues 5 being employed for securing the ends of each band together.

30 Extending between the two bands 3—4, are two bars 6 which are secured at 7 to said bands, at substantially diametrically opposite points. Riveted or otherwise secured to upper portions of the bars 6, are two vertical plates 8 preferably of substantially triangular form as seen in Fig. 1. Two legs 9 have their upper ends loosely pivoted at 10 to the plates 8 respectively, said legs normally lying at the outer sides of the bars 6,

40 in which positions they may be held by spring clips 11 secured to the lower ends of said bars. Two substantially vertical levers 12 are fulcrumed between their ends at 13 to the plates 8 respectively, at points spaced above the pivots 10, the upper ends of said levers being connected by a curved handle portion 14 extending part way around the periphery of the bag B, while the lower ends of said levers are pivotally and

45 slidably connected at 15 with the legs 9, at points spaced below the leg pivots 10. Preferably, a coiled spring 16 is connected with the upper end of one of the levers 12 to swing these levers in leg-retracting direction, as soon as the bag is lifted and the legs 9 are free from the ground. When the legs

swing inwardly they snap into the clips 11 and are thus securely held against accidental projection.

The plates 8 are provided with cams 18 60 which may well be formed by outwardly stamping portions of said plates. These cams are disposed in the outward paths of the legs 9 and as these legs are swung outwardly away from the bag B to or substantially to the position of Fig. 1, the cams 8 outwardly swing said legs away from each other into diverging relation as shown in Fig. 2, thus insuring that the leg-supported bag shall not accidentally tip laterally. To 70 further insure against tipping and slippage of the bag, the band 4 is preferably provided with a shoe 19 having pointed ground-engaging portions 20.

75 Preferably used with the parts above described, are two curved metal straps 21—22 which are secured to the plates 8 and extend around opposite portions of the bag B, assisting in holding said plates in rigidly spaced relation.

80 With the legs folded, the bag B may be carried by the usual handle H. When it is desired to support the bag in position to permit removal and insertion of clubs however, the levers 12 are rocked by means of the handle 14, thus outwardly swinging the legs 9 away from the bag and causing the cams 18 to swing said levers laterally away from each other as shown in Fig. 2. The bag may then be effectively supported upon the shoe 19 and the legs 9. When the bag is to be carried to another place, it is simply necessary to lift it by means of the handle H. When this is done, the spring 16 comes into play to restore the levers 12 and legs 9 to their normal positions, and in such positions, the legs 9 are held by the clips 11. Obviously, as the legs swing inwardly or outwardly with regard to the bag B and the cams 18 effect relative lateral movement of 85 said legs, the levers 12 must spring. These levers are of suitable material to permit such springing without danger of being permanently distorted from their proper shape.

90 Preferably the cams 18 are provided with stops 18^a to limit the outward swinging of the legs 9, and to hold these legs against excessive spreading, guide hooks 18^b are secured to said legs and slidably engaged with the lower edges of the cams.

105 It will be seen from the foregoing that novel provision has been made for attain-

ing the desired end, and while the details herein disclosed are preferable, attention is again invited to the fact that within the scope of the invention as claimed, variations 5 may be made.

I claim:—

1. In combination with a golf bag; two legs normally lying in retracted positions at opposite sides of said bag, means pivotally 10 mounting said legs, two substantially vertical levers fulcrumed at said opposite sides of the bag for movement substantially in the same directions as said legs, said levers being provided with a handle by means of 15 which they may be swung, and means connecting said levers with said legs at points spaced substantially vertically from the pivots of the latter, whereby swinging of the levers will swing the legs away from the 20 bag to operative positions.

2. In combination with a golf bag; two legs normally lying in retracted positions at opposite sides of the bag, means pivotally 25 mounting said legs, two substantially vertical levers at said opposite sides of the bag fulcrumed at points spaced substantially vertically from the pivots of said legs for movement in substantially the same directions as the latter, the upper ends of said levers being 30 connected by a handle portion which extends transversely at the periphery of the bag, and means slidably and pivotally connecting the lower ends of said levers directly with said legs at points spaced substantially vertically from the leg pivots.

3. A structure as specified in claim 1; together with means for swinging said legs away from each other as they are swung 35 away from the bag.

4. A structure as specified in claim 1; together with cam means for swinging said legs away from each other as they are swung away from the bag.

5. A golf bag support comprising two legs 40 to normally lie in retracted positions at opposite sides of the bag, pivots for said legs about which they may move outwardly away from the bag, two substantially vertical levers for disposition at said opposite sides of 45 the bag, the fulcrums of said levers being disposed to permit swinging of the levers in substantially the same directions as said legs, a handle for the upper ends of said levers, means connecting said levers with 50 said legs at points spaced substantially vertically from said leg pivots, and means for mounting said fulcrums and pivots upon the bag.

6. A golf bag support comprising two 60 legs to normally lie in retracted positions at opposite sides of the bag, pivots for said legs about which they may move outwardly away from the bag, two substantially vertical levers for disposition at said opposite 65 sides of the bag, the fulcrums of said levers

being disposed to permit swinging of the levers in substantially the same directions as said legs, a handle for the upper ends of said levers, means connecting said levers with said legs at points spaced substantially vertically from said leg pivots, means for swinging said legs away from each other as they are swung away from the bag, and means for mounting said pivots, said fulcrums and said swinging means upon the bag.

7. A golf bag support comprising two legs to normally lie in retracted positions at opposite sides of the bag, pivots for said legs about which they may move outwardly away from the bag, two substantially vertical levers for disposition at said opposite sides of the bag, the fulcrums of said levers being disposed to permit swinging of the levers in substantially the same directions as said legs, a handle for the upper ends of said 85 levers, means connecting said levers with said legs at points spaced substantially vertically from said leg pivots, cams in the outward paths of said legs for swinging them away from each other as they are 90 swung away from the bag, and means for mounting said pivots, said fulcrums and said cams upon the bag.

8. A golf bag support comprising two plates and means for mounting them in substantially vertical positions at opposite sides of the bag, legs pivoted to said plates for outward swinging from the bag, hand-operated levers fulcrumed on said plates for swinging in substantially the same directions 100 as said legs, and connecting means between said levers and said legs for swinging the latter.

9. A golf bag support comprising two plates and means for mounting them in substantially vertical positions at opposite sides of the bag, legs pivoted to said plates for outward swinging from the bag, hand-operated levers fulcrumed on said plates for swinging in substantially the same directions 105 as said legs, connecting means between said levers and said legs for swinging the latter, and means carried by said plates for swinging the legs away from each other as they are swung from the bag.

10. A golf bag support comprising two plates and means for mounting them in substantially vertical positions at opposite sides of the bag, legs pivoted to said supports for outward swinging from the bag, hand-operated levers fulcrumed on said plates for swinging in substantially the same directions 110 as said legs, connecting means between said levers and said legs for swinging the latter, and cams carried by said plates in the outward paths of said legs for swinging the latter away from each other as they are 115 swung away from the bag.

11. A golf bag support comprising upper and lower bands to surround the bag, ver- 120

- tical bars extending between and secured to substantially diametrically opposed portions of said bands, vertical plates secured to said bars, legs pivoted to said plates, substantially vertical levers fulcrumed on said plates and connected at their upper ends by a handle portion, the lower ends of said levers being connected with said legs for swinging the latter, and means carried by said plates 5 for swinging said legs away from each other as they are swung away from the bag.
12. A golf bag support comprising upper and lower bands to surround the bag, vertical bars extending between and secured to substantially diametrically opposed portions 15 of said bands, vertical plates secured to said bars, legs pivoted to said plates, substantially vertical levers fulcrumed on said plates and connected at their upper ends by a han- 20 dle portion, the lower ends of said levers being connected with said legs for swinging the latter, and cams carried by said plates in the outward paths of said legs for swinging the latter away from each other as they are swung away from the bag. 25
13. A golf bag support comprising two legs, two members to which said legs are pivoted, means for mounting said members at opposite sides of the bag, cams on said members in the outward paths of said legs 30 for swinging the latter away from each other as they are swung from the bag, together with guides on the legs slidably engaged with the lower ends of said cams to limit spreading of said legs. 35
- In testimony whereof I have hereunto affixed my signature.

FREDERICK M. SINGER.
